(57) **CLAIM**

The ornamental design for a fence, as shown and described.

DESCRIPTION

FIG. 1 is a front perspective view showing fence of the present invention.

FIG. 2 is an enlarged front perspective view of the corner picket assembly of the fence shown in FIG. 1.

FIG. 3 is an enlarged front perspective view of the corner picket assembly of the fence shown in FIG. 1; and,

FIG. 4 is a top plan view of the corner picket assembly of the fence shown in FIG. 1.

The fence pattern repeats as indicated. Portions of the fence are broken away to indicate indeterminate length.
